*Primary Examiner—Freda Nunn**Attorney, Agent, or Firm—Seed IP Law Group PLLC***[57]****CLAIM**

The ornamental design for a data-storage library front door, as shown and described.

DESCRIPTION

FIG. 1 is a top front right side isometric view of a Data Storage Library Front Door showing our new design;

FIG. 2 is a front elevational view thereof;

FIG. 3 is a top plan view thereof;

FIG. 4 is a right side elevational view thereof;

FIG. 5 is a bottom plan view thereof; and,

FIG. 6 is a left side elevational view thereof.

The data storage library is shown in broken lines for illustrative purposes only and forms no part of the claimed design.
